CLAIM

The ornamental design for a bag, as shown and described.

DESCRIPTION

FIG. 1 is a front perspective view of the bag showing my new design; and,

FIG. 2 is a side view thereof.

The dash dash broken lines on the strap depict stitching that does form part of the claimed design. The remaining broken lines located beneath the strap on the left hand side depict portions of the bag that form no part of the claimed design.

1 Claim, 2 Drawing Sheets
